UNITED STATES PATENT OFFICE.

HOWARD S. HEMENWAY, OF MONTVILLE, OHIO.

VEHICLE-AXLE.

SPECIFICATION forming part of Letters Patent No. 690,147, dated December 31, 1901.

Application filed September 7, 1901. Serial No. 74,693. (No model.)

To all whom it may concern:

Be it known that I, HOWARD S. HEMENWAY, a citizen of the United States, residing at Montville, in the county of Geauga and State 5 of Ohio, have invented Improvements in Vehicle-Axes, of which the following is a specification.

My invention relates to vehicle-axes, and has particular reference to the spindles and 10 their bearings forming a part thereof.

It has for its object the production of a spindle provided at its opposite ends with surrounding collars or ferrules adapted to sustain and take up the endwise wear of an 15 axle-box mounted thereon.

As a further object it contemplates the manufacture and employment of ferrules or sleeves which can be cheaply and readily applied to axles already in use, as well as new, 20 and which can be immediately removed and replaced in the event of wear or injury thereto.

In the accompanying drawings, which form 25 part of this application, and whereon corresponding letters indicate the same parts in the several views, Figure 1 is a side elevation of my invention, showing a hub-box in position upon its supporting-spindle. Fig. 2 is a longitudinal sectional view taken on the line 30 2 2, Fig. 1, showing hub-box, spindle, and detachable ferrules or bearings. Figs. 3 and 4 are views in side elevation, respectively, of the inner and outer ferrules aforesaid.

Reference being had to the drawings and 35 letters thereon, A indicates a vehicle-axle, which terminates in a spindle B and has formed thereon an enlargement C at the point where said axle and spindle merge one into the other. This enlargement C, as will be 40 observed by reference to Fig. 2, is reduced in diameter and screw-threaded, as at a, thus forming an abutment b, which surrounds and extends to the surface of spindle B.

Upon the threads a is detachably mounted 45 in screw-threaded relation an inner ferrule of novel construction, which constitutes an important feature of the present invention. This ferrule is substantially bell-shaped, having an internally-screw-threaded annular 50 body D, the walls whereof converge, as at E, to the surface of spindle B, which latter is

therefore snugly surrounded by the outwardly-projecting tapering and annular bearing-flange F. It will be observed that said detachable ferrule thus forms a double bearing for the inner end of an ordinary hub-box 55 G, its converging walls E at the same time serving to receive all inward thrusts of the axle-box, which are transmitted through an interposed washer c, all as will hereinafter 60 more fully appear. The opposite or outer extremity of spindle B is threaded, as at d, and furnished with the usual cap-nut H and flexible washer e; but the surface of said spindle within the confines of boxing G is further con- 65 figured by an additional screw-thread f, upon which is mounted a correspondingly-threaded outer sleeve I of cylindrical form for the purpose of sustaining the wear of the hub-box at that point, which would otherwise bear di- 70 rectly upon the spindle. When worn, the said sleeve I may readily be removed and replaced.

In practice the parts of my invention are arranged and assembled substantially as follows: The spindle B, if a new one, is originally formed with the enlargement C, reduced and threaded, as stated, and onto this is screwed the ferrule-body D, with bearing-flange F snugly inclosing spindle B. A washer c is thereupon slipped over said flange F until arrested by the adjacent walls E. Outer sleeve I is next secured to the extremity of spindle B by means of the screw-threads f, whereupon the hub-box (with its correlative wheel members) is slipped into place, 85 the inner end thereof bearing both upon the tapering bearing-flange F and the periphery of the ferrule-body D, its opposite end finding a bearing upon the outer sleeve I. Cap-nut H, with its washer e, then being drawn 90 up in the usual manner, the axle and depending parts are ready for service. Obviously the end thrust of box G is resisted by the walls E, which fact protects the axle or customary shoulder thereon from injury, while 95 at the same time all rotary wear and tear is sustained by the ferrule and sleeve aforesaid, which when badly worn may easily be removed without the laborious and expensive process of welding to the axle a new spindle. 100 It will further be observed that the detachable wearing parts or bearings of my inven-

tion may easily be applied to spindles which have become worn and which would otherwise be regarded as worthless. In such application and adaptation of the invention it is necessary only to turn out of the worn spindle the swell or tapering enlargement usually appearing at its inner end, to tap it with suitable threads *a f*, and to finally supply thereto the detachable parts aforesaid.

10 Having thus described my invention, what I claim, and desire to secure by Letters Patent, is—

15 1. In a vehicle-axle the combination with a spindle and a suitable axle-box, of an interposed detachable ferrule located within the confines of the axle-box and threaded upon

the axle beyond the bearing-point of said box, substantially as described.

2. In a vehicle-axle the combination with a spindle and a suitable axle-box, of an interposed detachable ferrule having an annular tapering body located within the confines of the axle-box and threaded upon the axle beyond the bearing-point of said box, substantially as described.

25 In testimony whereof I subscribe my signature in presence of two witnesses.

HOWARD S. HEMENWAY.
